(57) **CLAIM**

The ornamental design for a folding knife and multitool, as shown and described.

DESCRIPTION

FIG. 1 is a front perspective view of the folding knife and multitool with a blade shown in an open position;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a front perspective view of the folding knife and multitool with a multitool shown in an open position;
FIG. 9 is a front elevation view of the folding knife and multitool of FIG. 8;
FIG. 10 is a rear elevation view of the folding knife and multitool of FIG. 8;
FIG. 11 is a right elevation view of the folding knife and multitool of FIG. 8;
FIG. 12 is a left elevation view of the folding knife and multitool of FIG. 8;
FIG. 13 is a top plan view of the folding knife and multitool of FIG. 8;
FIG. 14 is a bottom plan view of the folding knife and multitool of FIG. 8;
FIG. 15 is a front perspective view of the folding knife and multitool shown in a closed position;
FIG. 16 is a front elevation view of the folding knife and multitool of FIG. 15;
FIG. 17 is a rear elevation view of the folding knife and multitool of FIG. 15;
FIG. 18 is a right elevation view of the folding knife and multitool of FIG. 15;
FIG. 19 is a left elevation view of the folding knife and multitool of FIG. 15;
FIG. 20 is a top plan view of the folding knife and multitool of FIG. 15; and,
FIG. 21 is a bottom plan view of the folding knife and multitool of FIG. 15.
The broken lines depict portions of the folding knife and multitool in which the design is embodied that are not considered part of the claimed design.
